UNITED STATES PATENT OFFICE.

JOHN W. FOLEY, OF BOGOTA, NEW JERSEY, ASSIGNOR TO WESTERN ELECTRIC COMPANY, INCORPORATED, OF NEW YORK, N. Y., A CORPORATION OF NEW YORK.

AMPLIFIER CIRCUITS.

Application filed December 15, 1923. Serial No. 680,785.

This invention relates to telephony, and aims to provide for faithfully and efficiently reproducing sound waves as electric current variations and faithfully and efficiently amplifying the current variations before transmitting them from a subscriber's station or substation over the line.

In the forms of the invention specifically shown and described herein for purposes of illustration, the amplifying means is supplied with direct current from the central station over the same conductor line used to transmit talking currents, and the output circuit of the amplifying device is connected to the line through a transformer so that the amplification may be faithful and efficient in spite of whatever difference there may be between the impedances facing the transformer.

20 The means for converting the sound waves into electric currents may also be supplied with direct current over the line used to transmit the talking currents. Thus, the transmitter may be of a type having high 25 modulating efficiency. If desired, the transmitter may be of the balanced type, to facilitate accuracy in the reproduction of sound waves as electrical variations.

In the drawings, Fig. 1 is a circuit diagram indicating a telephone system embodying one form of the invention and comprising a central station and two substations of similar type connected thereto, and Figs. 2 and 3 indicate modified types of substations 35 which may be substituted for the type of substation shown in Fig. 1.

In Fig. 1, subscribers' stations or substations 1 and 2 are connected to central station 3 by the two-conductor lines 4 and 5 respectively. Lines 4 and 5 may be of considerable length, and are dashed in the drawing, to indicate that the central station may be remote from the substations. The central station comprises a common battery or other 45 D. C. source 6, and a repeating coil having inductively related windings 7 and 8. At substation 1 is a telephone transmitter 10 working into an amplifier 11 through a transformer 12, the amplifier in turn working 50 into line 4 through a transformer 13 which preferably has a primary winding connected in series with condenser 14 across the anode and the cathode of the amplifier, a secondary winding connected in series with 55 a switch 15, an impedance 16, and a con-

denser 17 across the line 4. A telephone receiver 20 is connected across resistance 16 and a part of the secondary winding of transformer 13. The purpose of resistance 16 is to approximately balance the impedance of line 4 facing station 1, so that the receiver 20 will be substantially in anti-side tone relation (see Fig. 1 of G. A. Campbell Patent 1,264,472, January 22, 1918) to the transmitter 10 and amplifier 11 when switch 15 is closed. A calling bell 25 is connected in serial relation with condenser 14 across line 4 at station 1, this condenser and this bell being proportioned to respond to currents of ringing frequency sent to station 1 over line 4. It will be understood that signaling apparatus, ringing apparatus, and operators' listening in devices of any suitable type (not shown) may be provided at the central station.

The transmitter 10 may be of the push-pull microphonic type, as indicated in the drawing, which permits of high modulating efficiency and faithful reproduction of sound waves as electrical variations. The amplifier 80 is preferably of the electron discharge type, as indicated in the drawing.

The ratio of the transformer 13 is preferably such that it approximately matches the impedances facing its primary winding and its secondary winding, so that efficient and faithful amplification of the current delivered by a transmitter 10 and transformer 12 may be obtained. The plate-to-filament impedance of amplifier 11 will ordinarily be 85 high compared to the impedance facing the secondary winding of transformer 13 and therefore the impedance of the transformer in the direction from its primary winding to its secondary winding, will ordinarily be 90 made large in comparison to its impedance in the other direction.

Since the amplifier 11 is a voltage operated device, the transformer 12 is preferably a step-up transformer in the direction 100 from its primary to its secondary winding.

Station 2 is in all respects like station 1. The apparatus at station 2 is designated by the same reference characters as the corresponding apparatus at station 1 but primed. 105 The construction of the apparatus at station 2 will therefore be understood from the description above of the construction of the apparatus at station 1.

The operation of this system is as follows: 110

Normally, the weight of receiver 20 maintains receiver switch 15 open against its bias, and no current flows in transmitter 10 or amplifier 11. A subscriber at 1, for example, 5 wishing to talk with a subscriber at 2, removes receiver 20 from receiver switch 15, which thereupon closes, thus allowing D. C. to flow from source 6 through winding 7, the lower conductor of line 4, switch 15, conductor 27, the two sides of transmitter 10 and the two halves of the primary winding of transformer 12 in parallel, conductor 28, a retard coil 37, the filament of tube 11, leads 29 and 30, and the upper conductor of 10 line 4, back to source 6. This current energizes the filament of tube 11 and also renders the transmitter 10 operative. This current, flowing through the two halves of the primary winding of transformer 12 in opposite 15 directions, of course produces no magnetizing effect in the transformer.

On closing the switch 15, the subscriber at station 1 signals the operator at the central station, who connects station 1 with 20 station 2, and then clears himself from the line, after the subscriber at station 2 has removed receiver 20' from receiver switch 15'. Upon the closure of switch 15', direct current from source 6 renders transmitter 10' 25 operative and energizes the filament of amplifier 11' after the fashion in which transmitter 10 was rendered operative and the filament of amplifier 11 was energized upon the closure of switch 15.

When switch 15 closed, direct current was 30 also supplied to the plate circuit of tube 11, this current flowing from source 6, through winding 7, the lower conductor of line 4, the winding of bell 25, the primary winding of 35 transformer 13, the plate filament resistance of tube 11, leads 29 and 30, and the upper conductor of line 4, back to source 6. Similarly, when switch 15' closed, space current from source 6 was supplied to amplifier 11'.

When the system is in operation, condenser 17 prevents the direct current for 40 the plate circuit of tube 11 from being shunted away from the plate-filament resistance of the tube through resistance 16 and the secondary winding of transformer 13. The magnets of bell 25 serve as a choke coil in the lead for supplying direct current to the plate of tube 11. As will be apparent from the drawing, the alternating 45 components of the current in the output circuit of tube 11 flow through the condenser 14 and primary of transformer 13.

Fig. 2 shows a modified form of substation which may be substituted for the substations 50 in Fig. 1. In Fig. 2, a microphonic transmitter 10₁ of the unbalanced type is employed, instead of the balanced or push-pull type of transmitter shown at 10 in Fig. 1. Elements of the substation shown in Fig. 55 2 are the same as those designated by like

reference characters, respectively, in Fig. 1. In Fig. 2 the filament heating current flows between transmitter 10, and the filament through a retardation coil 37 and lead 28, a condenser 35 preventing flow of D. C. through the primary winding of transformer 12. Receiver 20 in Fig. 2 is connected in side tone relation to transmitter 10' and tube 11, whereas, as noted above, the receiver 20 in Fig. 1 is connected in anti-side tone relation to the transmitter 10 and tube 11. Consequently, Fig. 2 contains no balancing resistance corresponding to resistance 16 of Fig. 1.

Fig. 3 shows another form of substation which may be substituted for the substations shown in Fig. 1. In Fig. 3, there is shown at 10₂ a permanent magnet telephone transmitter or other type of telephone transmitter which does not require D. C. for its operation, instead of the transmitter 10 of Fig. 1. In Fig. 3, an auto-transformer 13₂ is employed, instead of the transformer 13 of Fig. 1 and anti-side tone circuit, such as disclosed in F. W. McKown Patent 1,524,402 of January 27, 1925, comprising a balanced receiver 20₂ is employed, instead of the anti-side tone circuit comprising receiver 20 employed in Fig. 1. Elements 4, 11, 12, 14 and 25 have functions similar to those of the elements of Fig. 1 which are designated by the same reference characters respectively. In Fig. 3, a receiver switch 15₂, comprising upper and lower contacts, is employed, instead of the receiver switch 15 of Fig. 1. A point on the winding of auto-transformer 13₂ intermediate the ends of that winding is connected to a point on the winding of receiver 20₂ intermediate the ends of the latter winding by means of a conductor 40; and the part of the receiver winding between the latter point and the upper contact of switch 15₂ embodies a resistance corresponding to the resistance 16 of Fig. 1, for balancing the impedance of line 4 which faces the substation of Fig. 3. In Fig. 3, the upper conductor of line 4 is connected to the positive pole of source 6 (not shown) instead of to the negative pole as in Figs. 1 and 2; and the lower conductor of line 4 in Fig. 3 is connected to the negative pole of the source 6, instead of to the positive pole as in Figs. 1 and 2.

In the operation of the substation of Fig. 3, when switch 15₂ is closed, direct current flows from the upper conductor of line 4, through the windings of bell 25, a lead 42, the upper contact of switch 15₂, the upper portion of the winding of receiver 20₂, lead 40, the lower portion of the winding of auto-transformer 13₂, and the filament of tube 11, to the lower conductor of line 4; and direct current also flows from the upper conductor of line 4, through lead 44, the lower contact of switch 15₂, the lower portion of the wind-

ing of receiver 20₂, lead 40, the lower portion of the winding of the auto-transformer 13₂, and the filament of tube 11 to the lower conductor of line 4. These direct currents 5 energize the filament of the tube 11, the latter current exerting the principal part of this energizing effect. Therefore, direct current for the plate-to-filament circuit of the tube flows from the upper conductor of line 10 4, through the windings of bell 25, lead 42, upper contact of switch 15₂, the upper portion of the winding of receiver 20₂, lead 40, the upper portion of the winding of the auto-transformer 13₂, and the plate filament 15 resistance of tube 11, to the lower conductor 20 of line 4; and direct current for the plate-to-filament circuit of the tube also flows from the upper conductor of line 4, through 25 lead 44, lower contact of switch 15₂, the lower portion of the winding of receiver 20₂, lead 40, the upper portion of the winding of auto-transformer 13₂, and the plate filament resistance of the tube, to the lower conductor 30 of line 4.

25 The general principles herein disclosed may be employed in many organizations varying from those illustrated without departing from the spirit of the invention as defined in the appended claims.

30 What is claimed is:

1. In combination, an element for amplifying electrical variations having an input circuit, an output circuit and an internal current path therebetween, a source of direct current remote from said element, a circuit for supplying direct current from said source to said path, and a transformer coupling said output circuit to the direct current supply circuit.

40 2. In combination, a circuit comprising a telephone transmitter, an electron discharge device fed from said transmitter and having an energizing circuit, a source of direct current remote from said transmitter and said device, means connecting said circuits to said source in parallel relation to each other, and a telephone receiver connected to said means in non-side tone relation to said transmitter and said device.

50 3. In combination, an electron discharge device having a space current circuit and having a cathode and a cathode heating circuit, said heating circuit including a telephone transmitter in series therein, a source of direct current, and means supplying said direct current from said source to said circuits in parallel with each other.

55 4. In a telephone system, an electric device comprising a sealed container having main electrodes and an electrified conductor, a telephone transmitter and a telephone receiver at said device, a source of direct current remote from said device for rendering said device and said transmitter active, and 60 local means at said device and actuated by

movement of said receiver for bringing said source into operation.

5. In combination, a source of direct current, an amplifier and a telephone transmitter remote from said source, said transmitter feeding said amplifier, two conductors for transmitting voice current energy away from said amplifier and for supplying energy of said direct current from said source to said transmitter and to said amplifier, and a telephone receiver connected to said circuit at said transmitter in non-side tone relation to said transmitter and said amplifier.

6. In combination, a substation comprising a telephone transmitter and an electron discharge amplifier having an anode, a cathode and a control electrode and having its cathode and its control electrode connected to said transmitter, a source of direct current remote from said substation, and a circuit for transmitting voice current energy away from said substation and for transmitting said direct current from said source to said anode, said cathode and said transmitter, said substation also comprising a telephone receiver connected to said second circuit and in non-side tone relation to said transmitter.

7. A telephone system comprising a subscriber's substation including an electrical wave amplifying element, a central station having a source of direct current energy thereat, a pair of conductors connecting said subscriber's substation and said central station, means for transferring electrical energy from said amplifying element to said conductors with voltage step-down, and means for conductively transferring electrical energy from said source of direct current energy and said conductors to said amplifying element.

8. An electrical wave amplifier having output terminals, a source of direct current remote from said amplifier, a circuit for supplying direct current from said source to said amplifier, an impedance changing transformer connecting said circuit and the output terminals of said amplifier, said transformer having a winding connected across said circuit, and means preventing said winding from shunting said direct current away from said amplifier.

9. In combination, an electrical wave amplifier, a calling bell at said amplifier, a source of direct current remote from said amplifier, and partly common circuits for transmitting ringing current to the winding of said bell and for supplying direct current from said source to said amplifier and said winding in series, whereby said winding serves as a retardation coil for substantially reducing variations in said direct current supplied to said amplifier.

10. A telephone system including a sub-

scriber's station, and a central station having a source of direct current energy thereat, a pair of line wires connecting said subscriber's station and said central station, a space discharge device at said subscriber's station having cathode, anode and grid or control elements, a transmitter at said subscriber's station, a connection from the positive pole of said source of direct current at said central station over one of said line wires to the anode of said discharge device, said connection including the primary winding of a speech transformer, a connection from the negative pole of said source over the other of said line wires to the cathode of said device, a circuit in bridge of said line wires including the secondary winding of said speech transformer and a stopping condenser, and means operatively relating said transmitter to the cathode and grid of said device.

11. A telephone system according to claim 10 in which said means operatively relating said transmitter to the cathode and grid of said discharge device comprises a circuit in bridge of said line wires and including in series relation said transmitter, the primary winding of a speech transformer and a heating circuit for said cathode, the secondary winding of said transformer being connected between said cathode and said grid.

12. In combination, a space discharge device, an electromagnetic receiver comprising a winding, a source of energy for said winding, means comprising two separate paths to supply the energy from said source to said winding, one of said paths including the space path of said space discharge device, and the other of said paths being in shunt relation to the space current path of said discharge device.

13. In a transmission system, a vacuum tube having a plate circuit, a receiver in said plate circuit having an energizing coil, a source of plate current in circuit with the receiver energizing coil, and an impedance in shunt to the plate circuit whereby current may flow from said source through the receiver energizing coil independently of the space current path of said tube.

14. In combination, a space discharge device, a source of space current therefor, an electromagnetic element having a winding for producing a steady field, and a circuit for establishing a path of steady current flow from said source through said winding independent of the space path of said space discharge device.

In witness whereof, I hereunto subscribe my name this 11 day of December, A. D., 1923.

JOHN W. FOLEY.
